UNITED STATES PATENT OFFICE.

JOHN WELLS, OF CAIRO, EGYPT.

GAS-CLEANING APPARATUS.

1,390,183.

Specification of Letters Patent. Patented Sept. 6, 1921.

Application filed September 30, 1919. Serial No. 327,442.

To all whom it may concern:

Be it known that I, JOHN WELLS, a subject of the King of Great Britain, of 36 Sharia Falaki, in the city of Cairo, Egypt, 5 have invented new and useful Improvements in Gas-Cleaning Apparatus, of which the following is a specification.

This invention relates to improvements in gas cleaning apparatus and comprises one 10 or more centrifugal tar extractors constructed in such a manner that the number of tar extractor units can be readily increased or reduced. In combination with the tar extractor units there may be provided a gas booster or delivery fan.

In the accompanying drawing:—

Figure 1 is a longitudinal central section, and

Fig. 2 an end elevation of a gas cleaning 20 apparatus constructed according to this invention.

As shown in this drawing,

A is a cast iron standard, with four bolt bosses B. The face of A at C is circular in 25 form with an annular groove or depression D. In the center of the standard A is a long bearing E attached to the standard A by bolts F and F, being made detachable so as to be easily replaced. Through the bearing E there runs a shaft G, to which are attached the booster fan H and the tar extraction paddles I. On the face of the standard A is a ring piece J provided with a gas outlet K, the edge of the ring piece J fitting 30 into the annular groove D. Within the ring piece J there is mounted on the shaft G a disk 1 with a series of paddles H, acting as a fan, blower or booster. Following the ring piece J is a division plate L with a hole 35 through the center. Following the division plate L is a tar extractor ring M fitted with a tar exhaust or outlet N, extending into a water seal. Within the tar extractor ring M is a disk 2 fitted to the shaft G and carrying a series of paddles or vanes I. The 40 ring M is followed by a division disk L' and then by a water service ring O which is supplied with water from the pipe 3.

The water service ring O is followed by a 45 division disk L'' and then by another tar extractor ring M'. Two such tar extractor units are shown but one or any convenient number may be provided.

After the final tar extractor ring there is 50 fitted an end plate P in the center of which

is an inlet for the gas. A pipe 5 passes through the plate P to admit water to the ring M'. The end plate P is further fitted with four bolt bosses 6 corresponding to the bosses B on the base plate A. When all 60 parts are in position bolts are passed through the bosses and the various rings and division disks are thus securely fastened in position. The various disks and their paddles mounted on the shaft G are held on the 65 proper positions by suitable distance pieces Q and the whole secured in position by means of the nuts and screw provided on the end of the shaft G.

Having described the construction of tar 70 extractors I will now describe the working thereof.

The end plate P is coupled, by means of pipes to the gas producer and the gas enters 75 thereby, where it meets with the water dripping from the pipe 5 after which it is immediately expelled to the periphery of the tar extractor ring by the paddles I revolving at great speed. The gas then passes back to the center of the extractor against the centrifugal force of the paddles on the other side 80 of the paddle disk. After being washed by water which drips from pipe 3 the gas passes through the second stage of the tar extractor into the booster ring J which 85 forces it to the engine or other consuming device.

The gas is ejected from the booster ring under pressure which varies according to the size of the disks and paddles and their 90 velocity.

What I claim as my invention and desire to secure by Letters Patent is:—

1. A gas cleaning apparatus comprising alternate rings and plates interlocking one 95 with the other and forming compartments, end plates one of which serves as a closure while the other is formed with a central gas inlet, bolts passed through said end plates from one to the other and clamping together 100 the assembled rings and plates, a horizontal shaft supported in the one end plate, and paddles mounted on said shaft and rotatable in said compartments and including imperforate plate portions alternating with said 105 first plates to provide a sinuous passage through the apparatus and about the paddles.

2. A gas cleaning apparatus comprising front and rear standards, the former of 110

which is formed with a central gas inlet, a horizontal shaft, a bearing mounted on said rear standard and supporting one end of said shaft, alternate rings and plates interlocking one with the other and forming circular gas chambers around said shaft, paddles mounted upon said shaft and working in said

chambers and alternating with said plates to provide a sinuous passage through the apparatus, and bolts passing through said end 10 plates from one to the other and clamping together the assembled rings and plates.

JOHN WELLS.
